TUNNELING EQUIPMENT

Application filed December 23, 1931. Serial No. 582,682.

This invention relates to improvements in tunneling equipment. At the present time it is customary to excavate and tunnel and, as the excavation proceeds, to support the roof and sides with tunnel lining consisting usually of wood or steel plates. Both the actual excavating work and the erection of the lining are hazardous occupations as cave-ins not infrequently occur, and sometimes 5 result in loss of life. Moreover the lining subsequently constitutes the outer form for the tunnel structure and is rendered unremovable as the bricking or concrete pouring proceeds. In long tunnels the cost of the labor and material involved in building the lining 10 is considerable and the material becomes a 15 total loss.

It is an object of this invention to provide tunneling equipment comprising a lining 20 consisting of a plurality of supporting members which are securely held at all times, in combination with means for advancing these supporting members from time to time longitudinally of the tunnel. The supporting 25 members are so arranged that men working beneath them are effectually protected against cave-ins, and since these members are movable longitudinally of the tunnel they are used again and again and eliminate the 30 necessity for building lining, thereby saving considerable labor and the loss of a great deal of material.

Another object of the invention is to provide a tunneling equipment consisting in part 35 of a lining comprising a plurality of supporting members the lateral margins of which engage the adjacent margins of other like members so that each member may be independently moved longitudinally of the 40 tunnel.

A further object of the invention is to provide a tunneling equipment consisting of a simple form of standard adapted to be rigidly held adjacent the inner extremity of 45 the last completed tunnel portion, and to provide power exerting means on said standard by which pressure is exerted against inward projections carrying by the supporting members so that the latter may be moved longitudinally in advance of the actual tunnel 50

building, and in doing so accomplish a portion of the digging with rapidity and at a relatively low cost.

Yet another object of the invention is to provide such an equipment wherein digging 55 shoes are provided on the forward extremities of the supporting members; and wherein these shoes are so mounted that they may be adjusted at varying angles; as it is found that adjustment of the shoes must be made to suit 60 the soil in which the work is being performed to insure their biting into the ground and retaining the forward extremities of their members in substantial alignment with the axis of the tunnel while they are being 65 forced forward.

With these and other objects and advantages in view which will become apparent as the specification proceeds, a preferred embodiment of the invention is hereinafter more 70 fully described with the aid of the accompanying drawings, in which:

Figure 1 illustrates a sectional view of a portion of a tunnel wherein the equipment is being employed.

Figure 2 is a front view of the equipment.

Figure 3 shows a portion of the rear of the standard, and

Figure 4 is an enlarged view of one of the digging shoes and the means for adjusting 80 its angularity.

Referring to the drawings, A designates one end of a completed tunnel portion, and B denotes earth some of which has been excavated for a continuation of the tunnel 85 structure. A standard 1 is arranged adjacent the inner side of the last completed tunnel portion A; this standard, which is preferably vertically disposed, has nuts 2 adjacent its opposite extremities in threaded engagement with which are screws 3. On the outer ends of the latter, rests 4 are provided which, in the present instance, are tightened against opposed portions of the inner face of the tunnel structure A; though the standard may be placed beyond, instead of within, the outer extremity of the tunnel structure 95 when desired.

A lining, comprising a plurality of supporting members 5, extends around the top 100

and sides of the excavation, partly encircling the tunnel section A, and projects forwardly thereof. The lateral margins 5a of these supporting members are so formed as to engage each other so that each member is permitted independent longitudinal movement. It will be noted that in the present instance the members 5 consist of lengths of conventional sheet piling though obviously any sheet with its lateral margins so flexed as to engage one another may be employed. Substantially centrally of each member 5 adjacent its forward extremity is an inward projection 6, which, in the present instance, 10 consists of a plate of I-beam section, and transversely of the forward extremity of each member is a digging shoe 7.

Here it may be noted that the supporting members 5 are of sufficient length to extend 20 a short distance rearwardly along the outer face of the last completed tunnel portion, along, and constitute the outer form of, the tunnel portion next to be completed, and also to project forwardly therebeyond.

25 A shaft 8 is journaled in the standard 1 and extends horizontally and substantially centrally therethrough. On one extremity of the shaft 8 a worm wheel 9 is provided and on its other extremity a boss 10a is rotatably mounted. The latter is integral with a radial guide 10 which in the present instance is of channel section. Rotatably supported by the standard 1 at right angles to the shaft 8 is a spindle 11 having a worm 12 thereon which cooperates with the worm-wheel 9, and on the said spindle is a crank 13, so that when the latter is turned the worm wheel 9 and shaft 8 are rotated thereby by turning the guide 10.

40 14 denotes a slide carried by the guide 10, said slide being preferably of channel section. Longitudinal adjustment of the slide is permitted by loosening bolts 15 which extend through openings in the said guide and 45 also through slots 17 formed longitudinally in the said slide. 18 denotes a power jack having supporting clips 19 and 20 around opposite extremities of its body. The clip 19 is secured to the outer extremity of the slide 14, and the clip 20 to diagonal braces 21 the opposite extremities of which are pivoted on lugs 14a integral with the slide 14.

The base of the jack 18 is placed against the front of the last completed tunnel portion A, and the crank 13 is turned until the jack is brought opposite one of the projections or I-beams 6. Between the bearing face of the jack plunger or ram 18a and the I-beam 6 suitable packing 21 is arranged.

60 The plunger 18a is then moved outwardly and one of the supporting members 5 is advanced. This may be continued until the supporting member 5 has been advanced the desired distance, though in practice it is 65 often found preferable to advance each mem-

ber successively as far as one forward stroke of the jack plunger 18a will take it.

In the construction shown a hydraulic pumping unit 22 of any conventional design is provided on a truck 23 so as to be readily transportable through the tunnel. A bracket 24 mounted on the truck may be employed for supporting the standard 1 when the screws 3 are so positioned that the feet 4 are not otherwise supported. The jack 18 is preferably double acting, and 25 and 26 denote flexible hose connecting the pump unit with opposite ends of the jack. 70 75

The digging shoes 7 which are provided transversely of the forward extremities of the supporting members 5 are so mounted that they may be inclined somewhat to the direction of the said members. This adjustment is desirable as best results are obtained by inclining the shoes according to the soil in which the work is being done. In the present instance this adjustment is made in the following manner: The inner sides of the shoes are apertured for the passage of screws 30 and 31. The screws 30 are in threaded engagement with the sides of the shoe apertures through which they pass and their outer extremities bear against the members 5, and the screws 31 are in threaded engagement with threaded apertures formed through the said members 5. By adjusting these screws it will be seen that the inclination of the shoes relative to their supporting members may be varied. 80 85 90 95

A sufficient number of supporting members 100 5 are employed to encircle the upper portion of the tunnel and to extend as far around the sides as may be deemed advisable. These members are all of substantially equal length. This length must be sufficient to extend rearwardly far enough along the last completed tunnel section to support the members coaxially with the tunnel bore; their intermediate portions must extend along the tunnel portion next to be constructed, and forwardly therefrom they must project sufficiently for the jack 18 to be inserted between the front extremity of the said next tunnel portion—when built—and the inward projections 6. 110 115 120

In most soils it is found that as the members 5 are advanced by the jack 18 the digging shoes will do a large proportion of the excavating. In the construction shown the clips 19 and 20 are connected to the slide 14 and braces 21 by pins 33 and 34 which are readily removable, so that, when desired, the jack 18 may be easily detached. 125

42 denotes a curved bracing member by which the forward extremities of the supporting members 5 are reinforced to prevent them from being inwardly flexed by the pressure of earth exerted on them. This bracing member is preferably of channel section the flanges of which extend inwardly and are 130

clear of the jack 18 which must be free to move about the axis of the shaft 8.

While in the foregoing the preferred construction of the invention has been described and shown it is understood that alterations and modifications may be made thereto provided they fall within the scope of the appended claims.

What we claim is:

- 10 1. An equipment of the character described comprising a tunnel lining consisting of a plurality of supporting members arranged side by side and having interlocking marginal portions which permit the movement in a 15 longitudinal direction of any one of said members independently, inward projections on said members, a standard, a jack, and mounting means for said jack so arranged on said standard that the jack may be positioned 20 opposite each of said projections in turn to force it and its supporting member in a longitudinal direction.

25 2. An equipment of the character described comprising a tunnel lining consisting of a plurality of flat supporting members laid side by side, the longitudinal margins of said members having interengaging portions thereon which engage the adjacent margins of the members next to them and permit the separate members to be inclined at varying angles to one another and also permit independent longitudinal movement of each member severally, an inward projection on each member, a standard, a jack, and supporting means for 30 said jack so arranged on said standard that the jack may be positioned in front of any one of said projections to move the member longitudinally to which said projection is attached.

35 3. An equipment of the character described comprising a tunnel lining consisting of a plurality of longitudinally arranged supporting members, interengaging margins formed longitudinally of said members which engage the adjacent margins of the members 40 which lie next to them, a curved bracing member adapted to bear against the inner sides of all said members and hold them so that they together retain the desired form against the top and sides of an excavation, inward 45 projections on said members, a standard, a jack, and mounting means on said standard for supporting said jack so that the latter may be positioned opposite any one of said projections to force it and the member to which 50 it is attached in a longitudinal direction.

55 4. An equipment of the character described comprising a tunnel lining consisting of a plurality of flat supporting members adapted to lie against the top and sides of an excavation, 60 interengaging portions formed along the longitudinal margins of said members which project laterally from said members, said portions being so arranged that each member may be disposed at varying angles to the members contiguous to it and so that any one mem-

ber may be independently moved in a longitudinal direction, inward projections on said members, a standard, a jack, means on said standard for supporting said jack so that the latter may be correctly positioned to exert 70 pressure against any one of said projections and move its member longitudinally, and an arched bracing member arranged transversely of said members which supports their interengaging margins and holds said members in their desired relative positions against the top and sides of an excavation without interfering with the longitudinal movement of 75 said members.
